UNITED STATES PATENT OFFICE

FRANCIS J. McAVOY, OF NEWARK, NEW JERSEY, ASSIGNOR OF ONE-HALF TO HIMSELF
AND ONE-HALF TO FRANK J. KENT, OF NEW YORK, N. Y.

TRAIN-CONTROLLING APPARATUS

Application filed June 4, 1924, Serial No. 717,710. Renewed June 21, 1929.

This invention relates generally to train controlling apparatus and more particularly to the construction of a trip device operable by a passing train when a condition of danger exists for actuating the brake applying mechanism on the train.

A general object of the invention is to provide a device of the general character referred to which will be invariably operated 10 when danger conditions exist in the controlling traffic section and which will be safeguarded against snow and ice and other adverse weather conditions.

The invention includes a vertically moving 15 tripping plunger which, with an actuating arm or lever therefor, is normally housed in a weather-tight casing securely anchored in the roadbed. A plunger for rocking the arm to elevate the tripping plunger to operative position projects from the casing adjacent one of the traffic rails where it will be engaged and depressed by the flanges of the car wheels passing along the rail. Normally the plunger does not engage the rock arm, the 20 plunger falling short of reaching the arm so that a gap normally exists between the lower end of the plunger and the adjacent end of the arm beneath.

In order to effect the actuation of the arm 25 by the plunger, a control arm which is normally held in an inoperative position by a magnet which is maintained in energized condition when safety conditions obtain in the block with which the magnet is associated, 30 is moved by a spring to a position to fill the gap between the plunger and the arm and thereby bring about the operation of the arm and the trip plunger when the controlling magnet is deenergized in response to a danger condition.

Other features of the invention will be hereinafter referred to.

Figure 1 is a plan view with parts broken 45 away showing a train control tripping device embodying the invention.

Figure 2 is a view in longitudinal vertical section of the device shown in Figure 1.

Figure 3 is a view in vertical section and 50 elevation of train-carried controlling ap-

paratus and showing its operative relation to the trip device shown in Figure 1.

Figure 4 is a diagrammatic view showing a railway track block and the electrical equipment for controlling the trip device. 55

Figure 5 is a view in vertical section of a modified form of trip actuating plunger for use in the device shown in Figure 1.

Figure 6 is a view from underneath of the device shown in Figure 1. 60

Figure 7 is a view in side elevation of still another form of trip actuating plunger.

Figure 8 is a plan view of the device shown in Figure 7. 65

Referring to the drawings for a more detailed description of the invention a casing or housing 10 is adapted to be mounted in a railway roadbed with one end thereof securely attached to a traffic rail 11 by clamping engagement with the base flange 12 of the rail as at 13 in Figures 1 and 2 of the drawing. The elongated casing 10 is arranged to extend away from the rail to a point which locates a vertically movable trip plunger 15 mounted therein midway between 70 the traffic rails. 75

The trip plunger 15 normally occupies a retracted and lowered position indicated in full lines in Figure 2 of the drawing and is adapted to slide vertically in a gland or stuffing box 16 formed in the upper wall of the casing 10. The lower end of the plunger 15 is seated in a guide socket member 17 with which it has vertically movable relation. An offset 18 formed at a mid-portion of the plunger provides a recess in which is received the rounded end 19 of an operating lever 20 and a spring interposed between the offset 19 and the top of the casing 10 normally holds the plunger in its lowered position. 80

The operating lever 20 is pivoted at 21 on a bracket 22 attached to the bottom of the casing 10 in a position adjacent the end 23 of the casing which is attached to the traffic rail 11. An actuating plunger 24 extends through a stuffing box 25 in the casing 10 in a position adjacent the rail where the flanges of train wheels passing along the rail will engage and depress the plunger to thereby rock the operating lever and elevate the trip plunger 15, 85 90 95 100

under certain operating conditions, into position to engage a brake controlling device carried by the train.

The actuating plunger or piston 24 is provided with a spring 26 mounted in a recess in the plunger into which an abutment stud 27 mounted on a shoulder 28 on the casing 10 projects. The plunger is provided with an offset stem 29 which overlies the end of the lever 20 but is spaced therefrom so that a downward movement of the stem 29 normally fails to engage and operate the lever 20.

In order to effectuate the operation of the lever 20 by the downward movement of the plunger stem 29 a control arm 30 is pivoted at 31 on the lever 20 for horizontally swinging movement to swing the extended end 32 of the arm into and out of position in the space between the lower end of the actuating stem 29 and the end of the operating lever 20. A spring 33 constantly exerts a pull tending to swing the control arm into operating position but the arm is normally held in inoperative position against the pull of the spring by a magnet 34 mounted on a bracket 35 attached to the lever 20. Upon deenergization of the magnet 34 the arm 30 which serves as an armature to the magnet is released to swing into operative position beneath the stem 29 as will be clear.

The magnet 34 is contained in a circuit 36 which also includes a battery 37. The circuit 36 is in turn controlled by a relay 38 controlled by the condition of the adjacent track block 39, the block circuit of which includes the battery 40 and circuit 41 connecting the rails at one end of the block and the circuit 42 including the coils of the relay 38 which connect the rails at the opposite end of the block. It will be seen that in an energized condition of the relay 38 the armature 43 thereof maintains the local circuit 36 closed and thereby maintains the magnet 34 in an energized condition to hold the arm 30 out of operating position. The entrance of a train into the block 39 short circuits the relay 38 as will be seen and brings about a corresponding deenergization of the magnet 34 to permit the arm 30 to swing into operating position, thereby setting the train-stopping mechanism in the block over which the train has just passed.

In Figure 3 of the drawing is illustrated train-carried control mechanism including a plunger 44 connected with a rock arm 45 which immediately controls a valve 46 in the train pipe brake controlling line. The plunger 44 is connected at its lower end to a pivoted plate 47 which is directly engaged and raised by the engagement therewith of the trip plunger 15 as the train passes the position of the casing 10 in the track. A dashpot device 48 in the plunger 44 operates to produce a slow return of the plunger to its lowered position following an actuation

thereof. A signal control circuit 49 including a battery 50 is arranged to be controlled by a contact bridging element 51 in the different positions which the bridging element takes in the rise and fall of the plunger 44.

In Figures 5 and 6 of the drawings is shown a modified form of actuating plunger 24 for the trip operating mechanism. This embodiment of the invention shows a flanged contacting member 52 mounted in a cushioned support 53 in the body of the plunger 24. This construction operates to absorb the shock of the blows to which the cap member 52 is subjected in the passing of the wheel flanges thereover. The actuating stem 29 in this construction instead of being formed integrally with the plunger body 24 as in Figure 1, is attached thereto by means of the screws 54 as is indicated.

In Figures 7 and 8 of the drawing still another form of actuating plunger construction is shown. A feature of this modification of the invention is the provision of approach arms 55 pivoted at 56 and resting at their free ends on shoulders 57 formed on the upper part of the plunger 24. The function of the arms 55 is to diminish the shock of the blow on the plunger 24 and practically to absorb the lateral component of the blow which is applied to the plunger construction by the moving car wheel flange.

What I claim is:

1. In train controlling apparatus, a trip device, a lever mounted in operative relation to said trip device, a train-operated piston adapted to move said lever, and block controlled means movable between said lever and said piston.

2. In train controlling apparatus, a vertically movable rod, a lever pivoted for vertical movement and having one end connected with the rod for operation thereof, a piston mounted for engagement by a train and spaced vertically above the other end of the lever, and a control member responsive to traffic conditions and adapted to be moved into the space between the piston and the end of the lever whereby to cause the movement of the piston to actuate the brake of the train.

3. In train controlling apparatus, a vertically movable trip plunger, a lever pivoted on a horizontal axis intermediate its ends and having one end connected with the plunger for operation thereof, a plunger located adjacent a traffic rail for operation by a car wheel flange passing thereover, the lower end of the plunger being spaced above the other end of the lever, a control arm pivoted for horizontal movement on the upper surface of the control lever and with one end thereof adapted to enter the space between the wheel operable plunger and the lever, a magnet carried by the lever and controlled by traffic conditions to normally hold the control arm in withdrawn position, and spring means for

moving the control arm into position between the plunger and the lever when the magnet is deenergized.

4. In train controlling apparatus, an elongated casing attached at one end to a traffic rail and extending to a position between the rails, a vertically movable trip plunger mounted in the extended end of the casing, a lever mounted for vertical movement in the casing and having one end connected to the trip plunger for operation thereof, a plunger operation by a car wheel, the lower end of the plunger being spaced above the adjacent end of the lever, a control arm pivoted for horizontal movement on the upper surface of the control lever and with one end thereof adapted to enter the space between the wheel operable plunger and the lever, a magnet carried by the lever and controlled by traffic conditions to normally hold the control arm in withdrawn position, and spring means for moving the control arm into position between the plunger and the lever when the magnet is deenergized.

5. In train controlling apparatus, an elongated casing attached at one end to a traffic rail and extending to a position between the rails, a vertically movable trip plunger mounted in the extended end of the casing, a lever mounted for vertical movement in the casing and having one end connected to the trip plunger for operation thereof, a plunger mounted in the other end of the casing for operation by a car wheel, the lower end of the plunger being spaced above the adjacent end of the lever, a control arm pivoted for horizontal movement on the upper surface of the control lever and with one end thereof adapted to enter the space between the wheel operable plunger and the lever, a magnet carried by the lever and controlled by traffic conditions to normally hold the control arm in withdrawn position, spring means for moving the arm into operating position when the magnet is deenergized, spring restoring means for the plungers, and stuffing box devices in the casing through which the plungers extend.

6. In train controlling apparatus, a trip member mounted in the trackway and arranged to be moved to a raised position under danger conditions, a train controlling plunger carried by a vehicle and extending downwardly below the level of the trip member when the trip member is raised, a hinged member supporting the lower end of the plunger and adapted to be engaged by the raised trip member and to swing upwardly to lift the plunger, and a shock absorbing spring connection between the hinged member and the plunger.

7. Train controlling apparatus comprising a trip rod, a pivoted lever having one end arranged to operate the rod, a piston mounted for train engagement and spaced from the other end of the lever, and a control member

responsive to traffic conditions and adapted to be moved into the space between the piston and the end of the lever whereby to cause the movement of the piston to actuate the brake of the train.

In testimony whereof I affix my signature. ⁷⁰
